US0D1017136S

(12) **United States Design Patent** (10) **Patent No.:** **US D1,017,136 S**
(45) **Date of Patent:** **** Mar. 5, 2024**

(54) **ABRASIVE SKIN TREATMENT DEVICE**

(71) Applicant: **Telebrands Corp.**, Fairfield, NJ (US)

(72) Inventors: **Ajit Khubani**, Saddle River, NJ (US);
Mohan Rajasekaran, Watertown, CT (US)

(73) Assignee: **Telebrands Corp.**, Fairfield, NJ (US)

(**) Term: **15 Years**

(21) Appl. No.: **29/763,760**

(22) Filed: **Dec. 23, 2020**

(51) **LOC (14) Cl.** **28-03**

(52) **U.S. Cl.** **D28/59**

(58) **Field of Classification Search**

USPC D28/57, 58, 59; D24/133, 146;
132/75.6, 76.4
CPC A61B 17/54; A61B 2017/320004; A45D
2200/1054; A45D 29/00

(57) **CLAIM**

The ornamental design for an abrasive skin treatment device, as shown and described.

DESCRIPTION

FIG. 1 is a top, front, left side perspective view of an abrasive skin treatment device showing our new design; FIG. 2 is a rear elevation view thereof; FIG. 3 is a front elevation view thereof; FIG. 4 is a right side elevation view thereof; FIG. 5 is a left side elevation view thereof; FIG. 6 is a top plan view thereof; and, FIG. 7 is a bottom plan view thereof.

The broken lines represent portions of the abrasive skin treatment device that form no part of the claimed design.

1 Claim, 7 Drawing Sheets
